UNITED STATES PATENT OFFICE.

CALVIN V. FRIEND, OF PORTERVILLE, CALIFORNIA, ASSIGNOR OF ONE-HALF TO GEORGE D. AVERY, OF PORTERVILLE, CALIFORNIA.

WRENCH.

No. 868,652.

Specification of Letters Patent.

Patented Oct. 22, 1907.

Application filed May 20, 1907. Serial No. 374,655.

To all whom it may concern:

Be it known that I, CALVIN V. FRIEND, residing at Porterville, in the county of Tulare and State of California, have invented certain new and useful Improvements in Wrenches, of which the following is a specification.

This invention comprehends a certain new and improved construction of wrench of that general type in which the jaw stock is rotatably adjustable with respect to the handle, in which special provision is made for relatively adjusting the clamping jaws, and the said invention primarily seeks to provide a wrench of the general type stated, of a simple and inexpensive construction, in which the parts are coöperatively arranged for quickly effecting the rotary adjusting of the jaw, for setting the jaws and locking them to their set position, and for quickly releasing the jaw stock to adapt the same for ratchet wrench purposes.

With the above and other objects in view, my invention consists in the detailed arrangement and combination of parts hereinafter fully described, specifically pointed out in the appended claims, and illustrated in the accompanying drawings, in which:

Figure 1, is a perspective view of my improved construction of wrench, the jaws being disposed in a fixed position and in longitudinal alignment with the handle and held locked to such position by primary or main jaw locking device. Fig. 2, is a similar view, the jaw stock being held at an angle to the handle to act as a ratchet wrench. Fig. 3, is a longitudinal section of my wrench taken on the line 3—3 of Fig. 1. Fig. 4, is a rear elevation of the head end of the handle, the cap plate being removed to illustrate the correlation of the ratchet or pawl device and the notched end of the jaw stock. Fig. 5, is a longitudinal section taken substantially on the line 5—5 on Fig. 4. Fig. 6, is a detail view of the stock and the sliding jaw. Fig. 7, is a detail view of the supplemental lock or ratchet. Fig. 8 is a detail perspective view of the slidable member 14 hereinafter referred to.

In the practical application of my invention, the handle 1 has its head portion 10 formed with a transverse bore 11 of uniform diameter throughout, the rear end of which, at the lower edge, merges with a longitudinal recess 12 in the rear face of the head, in which operates the supplemental locking device or ratchet pawl presently described in detail.

On the front face, the handle has a longitudinal or dove-tailed recess 13, in which is slidably held the main locking device which is in the nature of a long member 14 suitably shaped in cross section to engage the dove-tailed recess 13 and having its upper end formed with an outwardly projected heel 14^a, the purpose of which is readily apparent from the drawings.

The jaw stock or head 20 has an integral circular hub 55 which is of a length equal that of the bore in the handle head portion 10, in which it is rotatably mounted as clearly shown in Fig. 3.

The head portion 21 has a longitudinal groove 21^a that extends from the fixed jaw 20 down through the bottom of the said portion 21, and the latter at the extreme lower end, has a recess 22, into which the heel 14^a of the locking member 14, fits when the jaws are in the fixed position, as shown in Fig. 1.

3 designates a movable jaw that has a shank 30 slideable in the groove 21^a, and provided with a threaded aperture 31 for engaging the threaded end 40 of the adjusting screw 4, where the smooth end passes through a smooth aperture 41^a, the fixed jaw has a turning head 42 that rests on the upper side of the jaw 2, it being understood that by turning the said screw in either direction, the movable jaw can be slid up or down, as desired.

By referring now more particularly to Figs. 2, 4 and 6, it will be noticed that the rear end of the hub 2 has 75 a series of straight radial notches 2^a in its peripheral edge with which coacts the supplemental locking device or ratchet pawl, that automatically interlocks with the said notches when adjusted therefor. This device consists of a round shank 6 rockably held in 80 the groove 12, by means of the strap 16, it being also mounted in said groove to slide in the direction of the hub 2, and is automatically forced in said direction with its locking end projected within the bore 11 by a spring 18. The lower end of the shank 6 has a finger 85 piece 60, by means of which the said shank can be rocked to bring the upper end, which has a single beveled edge, in position to interlock with the ratchet end of the hub 2 for either direction of rotation of the jaw.

So far as described, to adjust the jaws to the fixed 90 position, shown in Figs. 1 and 2, the jaw stock is turned to bring the jaws in the longitudinal plane of the handle, to which position they are held by sliding the locking member 14 into engagement therewith, it being understood, by sliding said member 14 down, the 95 jaw head will be held to turn freely in its bearing on the head 10, the downward sliding of the member 14 being limited by the stop 15 as shown.

To protect the ratchet end of the jaw stock and the locking end of the ratchet, a cap 19 is secured over the 100 said parts, said cap also serving as a means for holding the screw 20^a, that engages the hub 2, and thereby keeps the rotary jaw head mounted in the handle head.

From the foregoing description taken in connection with the accompanying drawings, the manner in which 105 my invention may be used and the complete construction will be readily apparent. By reason of mounting the jaw head and combining it with the ratchet and

pawl devices, and arranging the pawl 6 in the manner shown, the wrench may be used as a ratchet wrench operable in opposite directions by simply adjusting the pawl 6.

- 5 To secure the jaw head in position to form an ordinary monkey wrench, the member 14 is slid into a locked engagement therewith, as shown in Fig. 1.

Having thus described my invention, what I claim and desire to secure by Letters Patent, is:

- 10 1. A wrench comprising a handle head having a transverse bore, a jaw head that includes an adjustable jaw member, said head having a hub for fitting on the bore in the handle, said hub having a series of straight radial notches in its peripheral edge, the jaw head having a recess, a latch or pawl slidably mounted on one side of the handle to engage the jaw head recess, a pawl rotatably mounted on the other side of the handle, said pawl having a single beveled locking edge, means for automatically holding said edge in contact with the recessed end of the jaw hub, and means for holding the jaw head hub in the

bearing of the handle, all being arranged substantially as shown and described.

2. The herein described improved wrench, which comprises a handle having a head portion formed with a transverse bore, a jaw head formed with a hub rotatably mounted in the said bore, a cap secured to the outer end of the hub and to the bored head, a movable jaw slidably mounted on the other jaw, the said other jaw having a locking notch, and member slidably mounted on the front side of the handle for interlocking with the rotatable head, 30 the outer end of the hub having circumferential straight notches, a pawl rockably mounted on the rear face of the handle, said pawl having a single beveled ratchet edge adapted to be moved into position to be engaged by the said notch, the said pawl including a turning portion and a 35 spring for holding the said pawl to its turning positions all being arranged as shown and described.

CALVIN V. FRIEND.
